UNITED STATES PATENT OFFICE.

LAURENCE E. MEYER, OF SAN DIEGO, CALIFORNIA.

DRY-SLUICE PLACER-GOLD SEPARATOR.

1,283,857.

Specification of Letters Patent.

Patented Nov. 5, 1918.

Application filed June 26, 1917. Serial No. 177,011.

To all whom it may concern:

Be it known that I, LAURENCE E. MEYER, a citizen of the United States, residing at San Diego, in the county of San Diego and State of California, have invented a new and useful Dry-Sluice Placer-Gold Separator, of which the following is a specification.

My invention relates to a new device in sluices for separating the gold from sand or gravel, and the objects of my invention are, to provide a machine of the kind that will not require any water for treating the material; that will separate the gold from the sands and gravel by the use of air; that is simple of construction and easily transported from one place to another.

I attain these objects by the mechanism illustrated in the accompanying drawings, in which:

Figure 1 is a side elevational view of my device showing in dotted lines certain interior members; Fig. 2 is a side elevational view opposite to that in Fig. 1; Fig. 3 is an end elevational view with a portion broken away; Fig. 4 is a plan view of the separating chamber with the cover removed and showing the operating means; Fig. 5 is a detail sectional view through A—B in Fig. 1; Fig. 6 is a similar sectional view through C—D in Fig. 1, Fig. 7 is a sectional view through E—F in Fig. 6 and Fig. 8 is a longitudinal section of the machine with the blower and compressor parts in elevation for the purposes of illustration.

Similar characters of reference refer to similar parts throughout the several views.

The casing 1 is a box tightly closed at all points except at the ends *a* and *b*, and it is provided at one end with a curved portion 2 and at the other end with an upwardly inclined portion 3, and is mounted on upright supports 4 on the one side and on similar supports 5 on the other side. The supports 4 are mounted at their lower ends in a sill 9 and the supports 5 are mounted at their lower ends in a sill 10. A hopper 6 is mounted near the one end of the casing 1 at 7, which opens into the chamber 8 of the casing 1.

In the chamber 8 of the casing 1 are a plurality of longitudinally disposed guide members 11 and side guide members 14 which are each provided with plane surfaces 12 at an angle to each other so as to prevent the sand and gravel from lodging on the top

thereof. There is also provided in said chamber 8 a plurality of screw or worm conveyers 13 which are placed parallel to each other and parallel to the guide members 11, 60 and are located below and between the guide members 11 and between the side guide members 14 and the adjacent guide member 11.

There is also provided a plurality of 65 troughs 15 each of which is made in the form of a rectangular box and extends across the bottom of the casing 1 and fits tightly against said casing 1, and each covers an opening into said chamber 8 in casing 1. 70 These troughs are provided on their sides with extensions 16, which are adapted to slide into grooves in the keepers 17 mounted on the casing 1.

Mounted above the casing 1 is an air receiver 18 which is connected with an air compressor 19 by inlet pipe 20. Said air receiver 18 is connected by outlet pipes 21 with the said guide members 14 at 22. These side riffles 14 are hollow and are attached to 80 the inside of the side walls of the chamber 8 so that an air-tight chamber 23 is provided. Outlet pipes 24 connect the chambers 23 with the troughs 15. These outlet pipes 24 are bent and have the end portions 25 turned 85 so that the air in passing through the pipes 24 will be projected into the troughs 15 toward the middle of the chamber 8. An apron 26 is mounted in chamber 8 immediately below the hopper 6. It is attached at 90 one end to the rear wall of the hopper 6 and extends downwardly in the said chamber 8 some distance beyond the vertical opening in the hopper 6.

A cylindrical member 27 is revolvably 95 mounted in the supports 28 and 29. It is inclined sufficiently to cause the sand and gravel placed in it at the end *m* to move toward the screen 31 when it is revolved. These supports 28 and 29 are each provided 100 with revolving bearings 30 on which the member 27 revolves. A cylindrical screen member 31 is attached to the member 27 at 32 and is adapted to revolve with the member 27. There are provided two annular projections 105 33 and 34 on the member 31 which are adapted to fit into the grooves of the revolving bearings 35 and 36. These bearings 35 and 36 are each revolvably mounted in a support 37, which is mounted by means of bolts 110 38 in the upper part of the hopper 6.

On the extended end of member 31 is pro-

vided an annular pulley surface 39 which is adapted to carry a belt 40 which connects with a pulley 41 on the end of the shaft 42. Said screen may also be revolved by means 5 of cog-wheels. The shaft 42 is revolvably mounted in bearings on supports 43, which are securely attached to the upright supports 4 and 5 at 44 and 45. On the other end of said shaft 42 there is rigidly mounted a gear 10 46 which is adapted to be driven by a pinion 47 on the shaft 48. The shaft 48 is provided on its lower end with a screw gear 49 which is adapted to be driven by the pinion 50, which is firmly mounted on the shaft 51. 15 The shaft 51 is revolvably mounted in bearings on the supports 52 which are attached at their lower ends to the sills 9 and 10. Mounted on the shaft 51 back of the pinion 50 is a pulley 63. Another pulley 64 is 20 mounted on the shaft 54 of a rotary fan 55. A belt 56 is adapted to be placed on the pulleys 63 and 64 so that the revolving of the shaft 51 will cause the blades of the fan 55 on shaft 54 to force a current of air through 25 the outlet *n* into the curved portion 2 of the casing 1 at 0. Another belt 57 is adapted to rest on belt 56 and to extend to a driving means on an engine or other power means (not shown.)

30 Disposed on the shaft 42 are a plurality of gears 58 which are adapted to engage one with each of the pinions 59 which are attached to the screw conveyers 13 and by their action cause the said screw conveyers 35 to revolve.

There is provided a plurality of baffles 60 in the member 31 to facilitate the movement of the sand and gravel therein when the member 31 is revolved, and a plurality of 40 similar baffles *c* are provided in the member 27 for the purpose of aerating, disintegrating and drying the sand and gravel before it reaches the screen 31.

In order to catch the fine particles of gold 45 a supply of quicksilver 61 is placed in the troughs 15. Attached to the roof of the chamber 8, as shown by dotted lines in Fig. 1, are a plurality of projecting wings or baffles 62. These members 62 are each provided with a triangularly shaped end which extends downwardly from the roof of the chamber 8 and they are disposed in rows 50 across the chamber 8 immediately in the rear of the troughs 15 and directly above 55 the screw conveyers 13. They incline toward the rear of the chamber 8 and are adapted to spread the current of air forced through the chamber and also to cause the materials driven by the air in chamber 8 60 to fall to the floor of said chamber 8.

In operation the sand or gravel is thrown into the cylinder 27 at *m*. The cylinder 27 is revolved by the belt 40, thereby causing the sand and gravel to be agitated and carried toward the hopper 6. When the sand

or gravel enters the member 31 the fine material falls through the screen into the hopper 6 on to the apron 26 where it spreads out in a thin sheet and drops into the chamber 8 on the longitudinal guide members 11 70 and the screw conveyers 13. The air from the fan 55 blows through the material being treated as it drops from the apron 26 and causes the lighter material to be carried toward the rear of the chamber 8 and permits 75 the heavier material to drop and settle on the floor of the chamber 8 and on and around the screw conveyers 13. Owing to the inclination of the surfaces 12 of the longitudinal guide members 11 the material 80 drops more readily on the conveyers 13.

As the sand or gravel reaches the first of the troughs 15 the current of air from the receiver 18 entering through pipes 24, acting in conjunction with the current of air 85 from the fan 55, causes the contents of the trough 15 to be stirred up thoroughly resulting in the lighter material being carried out of the first trough 15 into the next one. Owing to gold being so much heavier than 90 the sand or gravel it will naturally drop to the bottom of the trough 15 and as the material passes over the succeeding troughs the gold will all be retained in some of the troughs, and the lighter sand and gravel 95 will be forced by the action of the screw conveyers 13 and the force of the air in the chamber 8 to the outlet *b* of said chamber 8. In order to catch the very fine gold a quantity of quicksilver may be used in the 100 troughs 15.

Having thus described my device, what I claim as new and desire to secure by Letters Patent, is:

1. The combination in a dry sluice placer-gold separator of a hollow casing having an opening at each end and a plurality of troughs disposed on its lower surface over openings into the chamber in said casing, a plurality of longitudinal guide members 105 disposed horizontally in said chamber above said troughs; two side members each having a chamber therein mounted in said casing; a plurality of longitudinal screw conveyers mounted in the chamber in said casing, each provided with a means for rotating the conveyer.

2. The combination in a device of the kind described, of a hollow casing provided with longitudinal guide members, troughs 120 and side members with chambers therein; air pipes connecting the chambers in said side members with the chamber in said casing, and a means mounted on the frame supporting said casing for furnishing air 125 from one source to the chambers in said side members and from another source directly to the chamber in said casing, all substantially as set forth.

3. In a device of the kind described, a 130

casing having a chamber therein, a plurality of troughs connected with said chamber, and two horizontal side members each provided with an air chamber therein mounted one in each side of said chamber in said casing, each having air passages from said air chamber into said troughs, substantially as shown for the purposes specified.

4. In a dry sluice placer-gold separator, the combination of a sluice box provided with longitudinal side members, troughs and longitudinal conveyer means, with a fan means, an air compressor means, an air storage means, a material conveyer means,

and a power means for operating said fan means and said air compressor means and causing two intersecting currents of air to pass through said sluice box, all operatively connected together for the purposes described.

In testimony whereof, I have hereunto subscribed my name in the presence of two subscribing witnesses.

LAURENCE E. MEYER.
